UNITED STATES PATENT OFFICE.

JAMES R. SPEER, OF PITTSBURG, PENNSYLVANIA.

IMPROVEMENT IN CLASPS FOR METALLIC HOOPS.

Specification forming part of Letters Patent No. 18,779, dated December 1, 1857.

To all whom it may concern:

Be it known that I, JAMES R. SPEER, of Pittsburgh, in the county of Allegheny and State of Pennsylvania, have invented a new and useful improvement in clasps or fastenings for metallic bands or hoops for packing cotton, hemp, wool, hay, or other articles which are packed in bales or bundles under pressure; and I do hereby declare that the following is a full, clear, and exact description thereof, reference being had to the annexed drawings, forming part of this specification in which—

Figure 1 is a perspective representation of my improved clasp detached from the hoops. Fig. 2 is a sectional representation of the clasp and hoop, showing the mode of attaching the clasp.

My invention consists of the use of a clasp or fastening of the shape shown in the drawings, through which the ends of the hoop are passed, and the projecting extremities bent over and inserted into an opening in the center of the clasp, as hereinafter described.

I am aware that clasps or fastenings for metallic bands have been used, but differing from mine not only in conformation, but essentially in the mode of attaching or fastening the band or hoop, the mode generally used being to link the bent ends of the hoop into each other and secure them from pulling apart by a slide passing loosely over the point of junction, while others depend for their security on the expansive force of the compressed bale or package.

My clasp and mode of attachment possess the advantages of great strength, security, and ease of attachment.

To enable others skilled in the art to make and use my improved fastening or clasp, I will proceed to describe more fully its construction and operation.

In the drawings, *a* is the clasp, which may be conveniently made of cast-iron. It is hollow throughout, and has a square aperture midway from either end, (marked *c*.) which perforates both the upper and lower side pieces, *d* *e*, of the clasp. These side pieces, *d* and *e*, are parallel to each other, and are separated about the thickness of three folds of hoop-iron, thus forming the longitudinal opening which receives the ends of the hoops. These

side pieces are united at the edges by the rims *b* *b*, which project above the surface of the side pieces, thus forming a recess for the ends of the hoops bent over.

In describing the side pieces and rims of my clasp, I do not mean to imply that these parts are separate, the whole being cast in one piece of the shape shown in perspective in Fig. 1.

The mode of using the clasp for fastening the ends of metallic bands is clearly seen by reference to Fig. 2.

The clasp is attached while the bale is under pressure. The hoop or band being passed around it, one end of the hoop, marked *x* in Fig. 2, is passed through the clasp between the side pieces, *d* and *e*, and is then bent round the edge of the under side piece, *e*, and, lying in the recess formed by the projecting edges of the rims *b* *b*, the extremity is passed into the square aperture *c*. The other end of the hoop, marked *z* in Fig. 2, is then pulled tight around the bale, and is passed through the longitudinal opening in the clasp, (entering, of course, at the opposite end from that at which *x* was introduced,) and passing entirely through the clasp over the end *z* of the hoop. The projecting extremity *z* being cut to the right length, is bent upward over the edge of the upper side piece, *d*, and, lying in the recess formed by the rims *b* *b*, the extremity is passed into the aperture *c*. The attachment is thus complete, and the clasp, not being liable to slip from its place, being held firm by the bent hoops, is not susceptible of accidental derangement.

To open the bale, it is only necessary to raise the extremity *z* of the metallic band out of the aperture *c* of the clasp, when the whole comes apart, and, the clasp and hook being uninjured, are ready for future use.

What I claim as my invention, and desire to secure by Letters Patent, is—

The use of a hollow clasp or fastening for metallic bands, of the shape shown in the drawings, through which the ends of the hoop are passed in opposite directions, and the projecting extremities bent over the clasp and inserted into an aperture in the middle of the clasp in the manner hereinbefore described.

JAMES R. SPEER.
